[57] **CLAIM**

The ornamental design for a combination reel housing and retractable dual cable unit for securing a bicycle, substantially as shown and described.

DESCRIPTION

FIG. 1 is a perspective view taken from the rear, above and somewhat to one side of the housing from which the retracted cable ends protrude, of a combination reel housing and retractable dual cable unit showing my new design;

FIG. 2 is a top plan view thereof, the bottom plan view being substantially a mirror image thereto;

FIG. 3 is a right side elevational view thereof, the left side being substantially a mirror image thereto;

FIG. 4 is a front elevational view thereof; and

FIG. 5 is a rear elevational view thereof.

FIG. 1

FIG. 2

FIG. 3

FIG. 4

FIG. 5
